UNITED STATES PATENT OFFICE

PHILIP EICKENBERG, OF MINNEAPOLIS, MINNESOTA.

BOX-HINGE.

1,171,601.

Specification of Letters Patent. Patented Feb. 15, 1916.

Application filed January 11, 1915 Serial No. 1,585.

To all whom it may concern:

Be it known that I, PHILIP EICKENBERG, a citizen of the United States, residing at Minneapolis, in the county of Hennepin and State of Minnesota, have invented certain new and useful Improvements in Box-Hinges, of which the following is a specification.

My invention relates to metallic boxes for installing electrical apparatus and has for its object particularly to provide a hinge for the cover of the box formed of the material of the box and of the cover and having the parts so constructed and related that when the cover is closed the hinge portion will be sealed from the outside atmosphere. The construction, also, is one which makes practicable ready and efficient assembling of the cover and box portion.

The full objects and advantages of my invention will appear in connection with the detailed description thereof and are particularly pointed out in the claims.

In the drawings, illustrating the application of my invention in one form, Figure 1 is a rear view of a box showing my hinge construction. Fig. 2 is a top plan view of the same. Fig. 3 is a transverse section view taken through the hinge. Fig. 4 is a sectional detail showing the manner of assembling the box and cover to form the hinged connection between the two. Figs. 5 and 6 are sectional details similar to Fig. 4 showing the position of the parts of the hinge when the cover is closed and open, respectively. Figs. 7 and 8 are enlarged inside views of portions of the cover and wall of the box showing the manner of forming the parts for the hinge.

As illustrated, the rear wall 10 of the box has a portion cut out at the top edge, as indicated at 11 in Figs. 4, 5, 6 and 8, said cut-out portion being formed into a tongue 12 having an outwardly-turned extremity or lip 13 and a curved bearing portion 14. The cover 15 of the box has tongues 16 cut out of the rear flange of said cover and bent outwardly at the edge 17 so as to leave a short section 18 of the cover flange, as best shown in Figs. 4 to 7 inclusive.

The manner of assembling the cover upon the box is well shown in Fig. 4. As there illustrated, the section 18 of the cover flange, which becomes the pintle of the hinge, is forced inside of the outwardly-curved lip 13 of the tongue 12. When the

cover is forced down from the position shown in Fig. 4, the tongue 12 snaps into the position shown in Fig. 5, where the outwardly-turned lip 13 engages the cover tongue 16 and the edge of the cover tongue 16 engages the curved bearing-portion 14 of the tongue 12. Also, the pintle piece 18 engages within the curved bearing-portion 14. When in this position the cover 15 is not only hingedly connected with the back wall 10 of the box, but the relative engagement of the parts effectively seals up the hinging portion, rendering the box dust-proof. The cover swings open upon the hinge formed by the pintle piece 18 within the curved bearing-portion 14 and is limited in its opening movement by engagement of the cover tongue 16 with the box wall 10 at the point where the tongue 12 is pressed out from said box wall.

It will be apparent that from the practice of my invention an exceedingly efficient box hinge may be formed directly out of the material of the box and cover, said hinge being capable of the utmost ease of assembling and having the very great advantage of sealing the openings which otherwise would be created by the formation of the hinge from the material of the box and cover walls.

I claim:

1. In combination with the overlapping rear and cover walls of a box, a hinge formed of the material of said walls and comprising a tongue cut on three sides from the cover wall so as to leave a portion of the material at the edge of the cover wall to form a hinge pintle, and a tongue cut from said rear wall and formed with a curved bearing-portion to receive and encircle said pintle, said pintle being rotatably secured to the box between said encircling tongue and the rear wall of the box.

2. In combination with the overlapping rear and cover walls of a box, a hinge formed of the material of said walls and comprising a tongue cut on three sides from the cover wall so as to leave a portion of the material at the edge of the cover wall to form a hinge pintle, and a tongue cut from said rear wall and formed with a curved bearing-portion to receive said pintle, said cover tongue being turned outwardly at an acute angle and the end of said box wall tongue being curved outwardly so that the pintle portion may be pushed under

the same and when the parts are assembled and the cover closed the edge of the cover tongue will engage the curved portion of the wall tongue and the edge of the wall tongue will engage the inside of the cover tongue to make a dust-excluding closure of the hinged parts.

In testimony whereof I affix my signature in presence of two witnesses.

PHILIP EICKENBERG.
